CLAIM

The ornamental design for a combined video tape recorder and television camera, as shown and described.

DESCRIPTION

FIG. 1 is a top, front and right side perspective view of a combined video tape recorder and television camera showing our new design;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a bottom plan view thereof;

FIG. 7 is a top plan view thereof; and,

FIG. 8 is a top, front and right side perspective view thereof, the view finder and handle being in an alternative position to that shown in FIG. 1.

FIG. 1

FIG. 2***FIG. 3***FIG. 4

FIG. 5

FIG. 6
